UNITED STATES PATENT OFFICE

PAUL R. G. BIEDERMANN, OF SAN FRANCISCO, CALIFORNIA

METALLIC SUCKER ROD GUIDE

Application filed March 25, 1929. Serial No. 349,608.

My invention relates to sucker rod guides for preventing the sucker rods from being damaged as they are operated in oil well practice, and also to provide an expeditious means for quickly attaching said guides to said rods and removing said guides therefrom.

Devices for this purpose have heretofore been proposed but they have failed in practice because of the difficulty had in placing them in position on the rods and also in removing them therefrom, said devices, being made of wood, quickly becoming broken and hence placed out of commission in a very short time, said known guides thus becoming a detriment rather than a help in protecting the rods. By the use of my invention all these deleterious effects are effectively overcome.

It is accordingly an object of my invention to provide a novel form of sucker rod guide or protective device comprising an elongated body, preferably made of metal, and equipped with means in the shape of a novel form of locking key, which key is adapted to be positioned entirely within said body, and in engagement with said body at a plurality of points, said key effectively holding said guide to the rods and at the same time permitting the speedy removal therefrom.

The above and further objects and advantages of my invention, as will hereinafter more fully appear, I attain by the device constructed in accordance with the specification and illustrated in the drawing forming a part of my application.

Reference is had to the accompanying drawing, in which similar reference characters denote similar parts. In the drawing,

Fig. 1 is a side elevational view of my invention applied to a sucker rod,

Fig. 2 is a vertical longitudinal section taken through the device, with the sucker rod omitted,

Fig. 3 is an elevational view of the locking key,

Fig. 4 is a side elevational view of Fig. 3, the dotted lines showing the position the ends of said key assumes when said key is in locking position with the guide,

Fig. 5 is a top plan view of Fig. 1,

Fig. 6 is a top plan view of Fig. 3, and

Fig. 7 is a transverse cross-sectional view taken on the line 7—7, Fig. 1, looking in the direction of the arrows.

Describing my invention more in detail, I provide an elongated, preferably integral body 2 constructed of suitable metal, such as cast iron, provided with a central bore 4, opening into a slot 6 leading externally thereto, which bore is adapted to have positioned therein the sucker rod 8, shown in fragmentary form in Fig. 1, said rod being adapted to be slipped into the body 2 through the slot 6, thus forming a quick means for positioning the guide upon said rod.

The body 2 of the guide is also preferably cylindrical in form and tapered at its bottom and top as at 10, and has its periphery cut away to provide the spaces 12 for the passage of the circulating medium. The body 2 is also provided with a pair of tapered grooves 14, outwardly bent as at 16, for a purpose presently to be explained.

To form an efficient means for locking the guide on the sucker rod 8 in detachable relation therewith, the tapered key 18 is provided, which key has a head 20, adapted to be struck by a hammer for the purpose of forcing said key into engagement with the body 2, said key, when the device is in position on said rod being entirely within said body, the reduced tapered side extensions 22 engaging in the grooves 14, the body of said key being curved or cylindrical so as to closely fit the sucker rod 8.

To form an efficient means for locking the key 18 in position within the guide, the lower end of said key is cut away as shown more particularly in Fig. 3, to provide a pair of extensions 24 which are adapted to be bent as shown by the dotted lines in Fig. 4, to engage with the extension slots 16 when the key 18 is driven home. If desired, the body of the key may be made of comparatively rigid material while the extensions 24 are more or less flexible, as in practice preferred.

When the device is placed in operative position, the rod 8 is slipped into the body 2 through the slot 6 and the key inserted in the top thereof, the extensions 24 being straight, enter the slots 14, and are driven home with

a hammer or other implement, and when said extensions reach the slot extensions 16 they are bent outwardly, the taper of the key and said extensions thus forming an efficient means for preventing said key from being forced out of place, but at the same time permitting its ready withdrawal, the device being quickly placed on the rod or removed therefrom when desired.

10 While I have thus described my invention with great particularity, it will be clear that it may be modified throughout a wide range. I accordingly do not propose to be limited to the exact details of construction shown and 15 described, but reserve the right in practice to make all modifications thereof that fall within the scope of the appended claims.

I claim as my invention:

1. A sucker rod guide comprising a body 20 provided with an axial bore therethrough and a slot communicating with said bore and opening out through the side of said body, said body being also provided with a pair of grooves juxtaposed to said slot, said grooves 25 each having an end extension directed outwardly to the outside of said body, and a key adapted to engage the sides of said slot and its ends the extensions of said grooves for detachably locking said body to said rod.

20 2. A device of the class described comprising an open-sided body provided with a through bore and a pair of grooves in said body, each of said grooves being tapered from one end to the other and provided with an 25 off-set portion whereby a locking key may be detachably held entirely within said grooves to lock said device in position.

3. A device of the class described comprising an open-sided body portion provided 30 with grooves, each having an off-set portion for receiving a locking key, said locking being accomplished by the bending of the lower portion of said key as it is forced within said grooves and held by said off-set portion.

45 4. A sucker rod spacer comprising a body provided with a through bore, and a pair of longitudinally tapered grooves, each having an off-set portion of substantial length at the end thereof, and a concavo-convex locking 50 key having a pair of longitudinally tapered side flanges adapted to slide in said grooves, and a pair of end extensions, adapted to be bent when engaging said off-set portions, whereby said key may be held in locking engagement with said body.

In testimony whereof I have signed my name to this specification.

PAUL R. G. BIEDERMANN.
